United States Patent Office.

PHILIPP SCHREYER, OF NEW YORK, N. Y.

Letters Patent No. 76,828, dated April 14, 1868.

IMPROVEMENT IN GAS-HEATERS.

The Schedule referred to in these Letters Patent and making part of the same.

TO ALL WHOM IT MAY CONCERN:

Be it known that I, PHILIPP SCHREYER, of the city, county, and State of New York, have invented a new and improved Gas-Stove; and I do hereby declare that the following is a full, clear, and exact description thereof, which will enable others skilled in the art to make and use the same, reference being had to the accompanying drawings, forming part of this specification, in which—

Figure 1 represents a sectional elevation of my improved gas-stove, taken on the plane of the line $z-z$, fig. 2.

Figure 2 is a plan or top view of the same.

Similar letters of reference indicate corresponding parts.

This invention relates to a new manner of arranging the burners and the framework of a gas-stove, so that the operation of all parts may be very effective and satisfactory.

The invention consists, first, in making the upper parts of the burners corrugated, or so that they project beyond the lower round part of the pipe, and that therefore air enters the burner directly at its junction with the pipe, besides entering the pipe through perforated passages provided for that purpose. Thereby the gas will be fairly mixed with oxygen, and will burn with a more intense heat than it would if it were not mixed with the air.

The invention also consists in a new manner of constructing the frame of the device, and in so shaping the frame with polygonal sides that a series of such stoves can be placed together, to form one large heating-apparatus.

A, in the drawing, represents the frame of my improved gas-stove. The same consists of V-shaped uprights, $a-a$, connected at their upper ends by a polygonal ring, b , and at their angle, where they are close together, by a block, c , as shown in figs. 1 and 2. Through the block c is fitted a pipe, C , to the upper end of which the burner is secured, while its lower end connects with a gas-pipe, B , from a suitable reservoir.

The burner is either single or branched into two or more arms, or the pipe C may be branched, as shown. The lower part, d , of each burner, D , is perforated, as at $f-f$, and is simply tubular, as shown. Around this tube d is fitted the upper enlarged part e of the burner, which is corrugated, or polygonal, or otherwise, so arranged, larger than the tube d , that an air-space is left between the outer side of d and the inner side of e ; as shown in section in fig. 1.

By this arrangement air will be conducted to the gas before it is lighted, without giving the gas any chance to escape through the air-holes. The perforations $f-f$ may be omitted if the spaces between d and e are large enough.

E is a plate or frame, resting upon the frame A , for the purpose of supporting the articles to be heated, or the vessels containing such articles.

By having the upper rings, b , of the frame A polygonal, and not round or oval, I am enabled to set a number of frames together without loss of room, and for obtaining a large heating-apparatus. The burners D , however, when they are made as described, are applicable and adaptable to frames of every description.

Having thus described my invention, what I claim as new, and desire to secure by Letters Patent, is—

1. The burner D , constructed as described, consisting of the corrugated upper tube e , fitted upon the perforated smaller tube d , as herein described, for the purpose specified.

2. Making the frame of a gas-stove polygonal, so that a series of such stoves can be set close together to produce one large heating-apparatus, as set forth.

3. A gas-stove, consisting of the V-shaped uprights $a-a$, polygonal rim b , block c , pipe C , and burner $d-e$, all made and operating substantially as herein shown and described.

PHILIPP SCHREYER.
